Patented Oct. 5, 1971

222,153

WALL RECEPTACLE FOR SOAP OR THE LIKE

Paolo Cilia, 638 Ovington Ave., Brooklyn, N.Y. 11209

Filed Feb. 18, 1970, Ser. No. 21,501

Term of patent 14 years

Int. Cl. D6—01

U.S. Cl. D33—25

Fig. 1.

Fig. 4.

Fig. 2.

Fig. 3.

FIG. 1 is a front elevational view of a wall receptacle for a soap embodying my new design;

FIG. 2 is a top plan view thereof;

FIG. 3 is a side elevational view thereof; and

FIG. 4 is a cross sectional view taken on line 4—4 of FIG. 1.

The broken line representation of a soap bar in FIG. 1 is for purposes of illustration only.

I claim:

The ornamental design for a wall receptacle for soap or the like, substantially as shown and described.
